UNITED STATES PATENT OFFICE.

GEORGE D. HASKELL, OF CONCORD, MASSACHUSETTS, ASSIGNOR TO UNITED STATES MACHINE GUN COMPANY, OF BOSTON, MASSACHUSETTS, A CORPORATION OF MASSACHUSETTS.

MACHINE-GUN.

1,379,339.

Specification of Letters Patent. Patented May 24, 1921.

Application filed October 10, 1917. Serial No. 195,812.

To all whom it may concern:

Be it known that I, GEORGE D. HASKELL, a citizen of the United States, and a resident of Concord, county of Middlesex, and 5 State of Massachusetts, whose post-office address is 40 State street, Boston, Massachusetts, have invented an Improvement in Machine-Guns, of which the following description, in connection with the accompanying drawings, is a specification, like 10 characters on the drawings representing like parts.

This invention relates to firearms and more particularly to machine guns and automatic guns, and has for its object more especially to provide improved means for air-cooling the same.

The objects and aims of the invention will be best understood from the following 20 description, taken in connection with the accompanying drawings, of several embodiments of the invention shown and described for illustrative purposes, it being understood that the invention in its true scope is 25 definitely set forth by the claims.

In the drawings:

Figure 1 is a side elevation of a part of a machine gun embodying one illustrative form of the present invention;

30 Fig. 2 is a longitudinal section of Fig. 1, the barrel and cooling sleeve surrounding same being shown in elevation;

Fig. 3 is a longitudinal section, similar to Fig. 2, of another embodiment of the 35 invention;

Fig. 4 is a longitudinal section, similar to Fig. 2, of a further embodiment of the invention;

Fig. 5 is a cross section on line 5—5 of 40 Fig. 1, on a somewhat enlarged scale;

Fig. 6 is a detail of one illustrative means for fastening the sleeve surrounding the barrel; and

Fig. 7 is a cross section on line 7—7 of 45 Fig. 4.

In the following description, only so much of the gun structure will be described as is necessary to an understanding of the present invention.

50 To the barrel 2 there is rigidly secured adjacent the rear end thereof and in any suitable manner, a sleeve-like member 4 surrounding said barrel and providing an air space 6 around the latter. Said member

4 is provided with a port 8, said port, in 55 the illustrative embodiments of the invention herein disclosed, being provided at the under side of said member 4 and being of sufficient size to allow free access of the outer air to the interior of said member. 60 It is to be understood, however, that said port could be otherwise located in said member or that several ports could be provided, suitably placed with good results; but the particular arrangement herein shown and 65 described is of special utility.

Adjacent the muzzle of the barrel there is removably secured to the latter a spider 10, said spider being herein shown as secured to said muzzle by a clamping screw 70 or screws 12. Said spider 10 has rigidly secured thereto by riveting or otherwise in any suitable manner a nozzle 14, surrounding the muzzle of the barrel and extending some distance beyond the muzzle of the 75 latter. This nozzle may be of any suitable shape, but that herein shown has proven very efficient.

That part of the barrel between the nozzle 14 and the member 4 is normally 80 enclosed by a cylindrical casing, said casing being of somewhat larger diameter at its ends which fit over the rear end of the nozzle 14 and the front end of the member 4, respectively, as clearly shown in Figs. 2, 3 85 and 4.

In accordance with the present invention, this casing is made in two parts, the lower part or half 16 being rigidly secured at its front and rear ends by riveting or in any 90 other suitable manner to the rear end of the nozzle 14 and the front end of the member 4, respectively, while the upper part or half 18 of said casing is intended to be movable to expose the barrel for a purpose hereinafter more fully described, and to that end is not secured to said nozzle 14 and member 4, but is mounted for swinging movement upon the lower half 16. Herein the upper part or section 18 of the 100 casing is hinged to the lower section 16, as shown in Figs. 1 and 5, in the embodiment of the invention shown in said figures, three such hinges 20 being used for the purpose, but it will be apparent that any other 105 means could be employed to permit the casing to be opened, without departing from the scope of the invention.

Any suitable means may be provided in accordance with this invention for securing the upper section 18 of the casing in closed position, such as one or more swing bolts 22 pivoted to ears 24 upon the upper section and adapted to coöperate in well known manner with ears 28 upon the lower section 16, said swing bolts being provided with wing nuts 26. The two sections 16 and 18 being closed and said wing nuts being loosened, the bolts 22 can be swung inwardly to engage between ears 28, whereupon by tightening said wing nuts the sections 16 and 18 of the casing will be securely clamped together. The ears 28 will preferably be provided with a downwardly projecting lip 30 at their outer edges, behind which the wing nut becomes seated when tightened, thus adding to the security of the fastening. Only one of said fastening means is herein shown in Figs. 5 and 6, but preferably one will be provided opposite each of the hinges.

In the embodiments of the invention herein shown, the barrel 2 is provided with a sleeve 32 that is longitudinally fluted or grooved or provided with longitudinal ribs, as shown at 34, upon its outer surface, said grooves, flutings or ribs, preferably extending spirally about said sleeve.

The sleeve 32 with its ribs or flutings 34 is intended to promote the dissipation of heat and thus assist in cooling the barrel, and that this may be accomplished as effectively as possible said sleeve and the flutings or ribs thereon will preferably be made of some material possessing a high coefficient of thermal conductivity, such as aluminum. The casing may also be made of similar material to the same end. For the same purpose, the sleeve with its ribs and the casing will preferably be blackened.

In the embodiments of the invention herein disclosed, the sleeve 32 is applied to a portion of the barrel only, herein the rear portion, that is to say to that portion which becomes the most heated by the firing of the gun, but it will be apparent that the sleeve 32 could be extended throughout a greater length of the barrel or even throughout the whole length thereof if that should be found expedient or desirable.

With the two sections 16 and 18 of the casing surrounding the barrel securely closed, the firing of the gun will at each shot expel a portion of the air from the nozzle 14 and thus cause a certain amount of the outer air to enter the rear end of said casing through the port 8, and in continuous firing a substantially constant or continuous flow of air will thus be produced along and about the barrel and sleeve 32 within said casing, the air entering at the rear of said casing and pouring out through the nozzle 14, and this continuous flow of fresh air over the

flutings or ribs 34 will carry off the heat radiated thereby, thus cooling the sleeve and barrel.

It is found in practice, however, that where bursts of firing are continuously prolonged beyond a certain point, say for example 1000 shots, the heat is generated or stored up within the casing more rapidly than it can be carried off by the draft of air through the casing and a point will inevitably be reached where the barrel becomes so heated that, in order to avoid injury to the gun, the firing must be suspended and the gun allowed to cool before firing can be resumed. It has been found, however, that owing to the great amount of heat that has become stored up within the casing the gun cools very slowly, for the firing having ceased there is no longer created a draft through the casing and the heat has little tendency to escape, being confined by the casing. To overcome this difficulty recourse has been had to standing the gun upon end in an attempt to create an upward draft of air through the casing, but it will be readily understood that such procedure is objectionable when the gun is in action, as thereby the position of the gun is revealed to the enemy. Furthermore, by such action, the lay or aim of the gun will be disturbed.

By the illustrative arrangement above described permitting the casing to be opened, means are provided whereby the gun can be quickly cooled whenever desired. Furthermore, this can be accomplished without changing the position of the gun or disturbing the aim, it being only necessary to unfasten the swing bolts 22 and throw back the upper section of the casing as soon as the firing ceases, thus affording free egress to the heat so that the gun is quickly cooled to a point where firing can be resumed.

In order to secure a tight closing of the casing and thus not impair the draft therethrough during the firing of the gun, the upper section 18 of the casing will preferably be provided with a recess 36 along each edge, see Fig. 5, into which fits a corresponding rib 38 provided along the inner edges of the lower section 16.

In Fig. 3, the inner wall of the casing is provided with annular projections 40 throughout a part of its length, thus bringing the circulating air into more intimate contact with the sleeve 32 at those points.

In Fig. 4, the casing is shown as provided with radially disposed ribs or fins 42 disposed longitudinally of its inner wall and with further radially disposed ribs or fins 44 extending longitudinally of its outer wall to assist in the dispersion of the heat. These fins or ribs 42 and 44 may be made of aluminum or any other good heat conductor, or, if integral with the casing, the cas-

ing itself may be made of that metal or material.

In the embodiment of the invention shown in Figs. 4 and 7, to form the upper and lower sections 18 and 16, the casing is divided through the two diametrically opposed horizontal ribs 42 and 44, and two divided portions of the rib 44 upon one side of said casing being hinged together at 46, as shown in Fig. 7, by three suitably spaced hinges for example, and the two parts of the divided rib 44 upon the opposite side of the casing being detachably secured together by swing bolts 48 each pivoted in a slot 50 of the upper part of said rib and engaging a slot 52 provided in the lower part of said rib. In this construction also, in order to secure a tight closure of the casing, the upper parts of the divided ribs 44 are provided with longitudinally extending ribs 54 that engage corresponding longitudinally extending recesses 56 in the lower parts of said ribs.

It will thus be seen that there is herein described apparatus in which the several features of this invention are embodied, and which apparatus in its action attains the various objects of the invention and is well suited to meet the requirements of practical use.

As many changes could be made in the construction described, and many apparently widely different embodiments of the invention could be constructed without departing from the scope thereof, it is intended that all matter contained in the above description or shown in the accompanying drawings shall be interpreted as illustrative and not in a limited sense.

Claims.

1. A gun having in combination, a barrel, a casing surrounding the same and extended forwardly beyond the muzzle of the barrel, air ports entering said casing near its opposite end, whereby firing of the gun will cause a current of air to enter the casing at said port, flow along the barrel to cool the same and escape at the outer end of the casing, said casing having outwardly extended heat radiating ribs thereon, the casing split longitudinally through a plurality of said ribs, and hinged to open along one of the rib

ends, recesses in two of the split portions of said ribs and beads on the opposite split portions of said ribs to enter the recesses whereby the casing may be opened throughout its length to further admit air within the same. 55

2. A gun having in combination, a barrel, an aluminum casing surrounding the same and extended forwardly beyond the muzzle 60 of the barrel, air ports entering said casing near its opposite end, whereby firing of the gun will cause a current of air to enter the casing at said port, flow along the barrel to cool the same and escape at the outer end 65 of the casing, said casing having outwardly extended heat radiating ribs thereon, the casing split longitudinally through a plurality of said ribs, and hinged to open along one of the rib ends, recesses in two of the 70 split portions of said ribs and beads on the opposite split portions of said ribs to enter the recesses whereby the casing may be opened throughout its length to further admit air within the same. 75

3. In a gun, the combination with the barrel 2 of an aluminum sleeve 32 thereabout, and a fixed casing member 16 therefor, having a nozzle 14 extending beyond the muzzle of the gun, said casing having 80 the port 8 at its rear end, outwardly extended ribs 44 thereon, the casing split longitudinally through said ribs and hinged thereat, to open along one of said ribs to admit air to the barrel throughout substantially the length thereof, two of said split rib portions having recesses 56 in the face of the same and the corresponding split rib portions having beads 54 thereon to enter said recesses when the casing members are 85 closed.

4. In a gun, the combination with the barrel 2, of the sleeve 4, having the port 8, spider 10 and nozzle 14, the casing comprising the closed section 16 and hinged section 95 18, swing bolts 22 on the section 18 adapted to coöperate with the ears 28 on the section 16; and the sleeve 32 on the barrel 2.

In testimony whereof, I have signed my name to this specification.

GEORGE D. HASKELL.
